UNITED STATES PATENT OFFICE

JOHN KAEFER, OF HAMILTON, OHIO, ASSIGNOR OF ONE-HALF TO GEORGE VAN WORMER, OF HAMILTON, OHIO.

PEN CLAMP.

Application filed October 30, 1925. Serial No. 65,747.

The invention relates to clamp devices of the character illustrated in the patent to Van Wormer, No. 1,314,916 of September 2, 1919, and may also be applied to various other forms of clamps, as discretion may dictate. The invention has for an object to improve the structural details of such devices to the end of simplifying manufacture, and facilitating their manipulation in use, as well as adding to the efficiency of the device as a clamp. It is also an important aim of the invention to improve the functioning of the device in conjunction with the flannel and worsted by which ink is fed to the pen devices. A further important aim of the invention is to effect clamping of pens efficiently at the same time that they are held in a manner to be quickly removable and also in such fashion that access of ink to the inner surfaces of the clamp is guarded against and tendency of the ink to spread to surfaces where it is not desired is overcome.

It is an advantage of my invention that, while retaining the advantages of the best prior devices, I have been able to so simplify it that but two main plates, two main shafts, and a means for rocking of one shaft are all that are required to embody the invention. At the same time, the principal elements are of such character as to be finished by very simple operations. Also, the device may be taken apart very quickly by the removal of a single fastening element, and when the parts are separated, they are few in number and of a character not liable to loss or misplacement easily.

Additional objects, advantages and features of invention reside in the construction, arrangement and combination of parts, as may be more fully understood from the following description, and the accompanying drawings, wherein—

Figure 1 is a left-hand end elevation of a clamp constructed in accordance with my invention showing a pen and worsted in place.

Figure 2 is a similar elevation of the opposite end of the device.

Figure 3 is a front elevation of the left end portion only, of the clamp (from the left of Figure 1).

Figure 4 is a top view of the clamping structure of Figure 3 with the pen and worsted removed.

Figure 5 is a cross sectional view on the line 5—5 of Figure 3.

Figure 6 is a similar view of the top member only of the clamp.

Figure 7 is a similar view of the bottom member of the clamp.

Figure 8 is a detail of one of the pens much enlarged.

Figure 9 is a fragmentary longitudinal sectional view of the clamp enlarged, showing the hinged connection of the clamping plate.

Figure 10 is a fragmentary longitudinal sectional view showing the clamp cam and its operating means.

Figure 11 is an inner face view of the bottom member of the clamp with the cam shaft laid in place thereon.

Figure 12 is a similar view of the top member.

Figure 13 is a fragmentary section showing the connection between the clamping screws 39, and Figure 14 is a section at right angles to Figure 13, with one of the screws removed.

There is illustrated a clamp comprising bottom and top clamp plates 15 and 16 respectively, which may be of any usual proportions required for such devices. It is an advantage of the construction that the plates may be made of considerable length without sacrificing rigidity or other features of efficiency essential to such appliances, and both elements are readily adapted to be cast so that little, if any, machining is required for completion in readiness for assembly. Both plates are customarily cast of aluminum, owing to its water repellent properties, and the fact that it prevents the spread of ink from the worsted and flannel. Openings for the hinge pin and notch bearings for the cam shaft, as well as faces on which certain cams bear, may be machined. The plates may have any customary ears, flanges or other elements required for mounting in various types of machines, the details of which need not be specifically shown, as they are well known.

The plates are formed with alined recesses 17 on their inner faces extending throughout their length, and stopping short of the ends a short distance. The recesses in each plate stop short of the front edges of the plate a suitable distance to provide a wide bearing, clamping or gripping face 18, between which pens may be properly clamped as hereinafter described. A multiplicity of transverse ribs 19 are

formed across the recess 17 in the plate 16, one such rib being at each end of the plate, and ribs 20 are formed across the plate 15. In each of the ribs an ear 21 is formed, all 5 the ears on both plates being aligned and apertured to receive commonly a hinge pin 22 having a slotted head at one end and at the other end engaged in a circular nut 23 set in a recess in the end of the plate 16. 10 The ribs of one plate are offset longitudinally from those of the other plate, so that ribs of one plate lie closely adjacent those of the other plate. The ribs 19 of the top plate are all formed with bearing notches 24 in 15 alignment, adjacent the forward side of the recess 17, the ears 21 being located adjacent the rear side of the recesses 17 in the plates. It should be noted that when the hinge pin 20 is in place the opposed inner faces of the 20 plates may lie in spaced parallel relation sufficient to permit a slight rocking movement of the plates on the hinge pin. The ribs 20 of the bottom plate at the ends opposite the bearing recesses 24 are smoothly 25 finished either with a planiform face parallel to the medial plane of the plate as at 28, or otherwise as found desirable, to allow proper bearing and wiping of cams thereagainst, to be described. At each end of 30 the bottom plate 15 the nearest rib 20 is located slightly inward from the end of the plate, and the end portion of the plate is formed with a cam bearing adapted to lie in the recess 24 of the end rib of the plate 16, and also with a larger recess adapted to receive the ear 21 at the end of the other plate, and in addition, at each end both 35 plates are formed with semi-circular recesses which together receive snugly the nut 23 by which the hinge pin is secured in place.

A rocking cam shaft 26 is provided having reduced parts adapted to set snugly in the bearing recesses 25, and provided with eccentric cams 27, all of similar form and with lobe portions similarly arranged radially of the shaft and adapted to bear upon the smoothly finished faces 28 of the ribs 20, so that upon rocking of the shaft the 40 adjacent portions of the plates will be forced apart, causing their front edges or jaw portions to be brought together, as will be understood. The shaft 26 is in the present instance formed with an angular end 45 projected at the left end of the clamp, upon which there is clamped a rocking arm 30, having a ball socket formed in the forwardly extending end thereof, in which there is 50 removably clamped the ball-shaped end of a thumbscrew 31 by which the cam shaft is 55 rocked. This screw is threaded in a rigid arm 32 formed integrally on the top plate 16 and projected longitudinally therefrom 60 a distance, being also offset from the top 65 thereof sufficiently to permit free movement

of the rocking arm 30 thereunder. Between the faces 18 of the plate there is engaged a continuous strip 33 of soft elastic rubber and clamped between this strip and one of the plates are the base portions 34 of the pens 35. This base is very thin, rectangular in form, and as broad as convenient for the proper spacing of pens when arranged in close relation. The pens may be formed with one or more points or feed 70 arms 36, as indicated in Figures 3 and 8. Customarily, this pen is stamped of sheet metal so as to form the base portion before mentioned, and one or more integral feed arms 36, by which the ink is carried directly to the paper or other material when the device is in use. The base of each arm terminates in a wider groove or recess 37 in a forward extension of the base plate 34, and in practice, the worsted 38 is secured 75 at one end closely around the base of the arm 36, and led directly upward and backwardly over the plate 16, upon which it rests, a flannel or other reservoir element being associated with the worsted in such manner as to supply ink in proper quantity thereto.

It is one of the most important features of my invention that the top plate 16 is formed with grooves 40, extending from the back edge or shoulder 41 of the plate forwardly and over the rounded front portion or jaw 42 to within a short distance of the clamping face 18 on the under side of the plate 16. These grooves are formed at right angles to the plate throughout its length and in such close parallel relation that the side of one intersects the side of the next adjacent groove, so that at any point where a pen may be located in the device, one or more worsted may be led from the arm or arms 36 of the pen and laid in respective grooves nearly or immediately in line with the base of the pen arm. The grooves are of such depth and width that the particular 105 worsted thread used for feeding the ink to the pen may lie in a groove loosely yet extending slightly above the groove so that flannel laid along the plate 16 over the grooves will rest lightly upon the worsted with sufficient contact to insure feeding of ink upon the flannel to the worsted by capillary action. It is an important advantage of this arrangement that there will be a much freer flow of ink to the worsted than under ordinary practice, where the worsted is laid upon a flat surface and the flannel superposed thereupon. The reason for this is readily understood by those versed in the art, it being well known that the ink can 110 flow between loosely arranged fibers more readily than between closely packed fibers. Consequently, where a flannel rests directly upon a worsted so as to compress or compact the fibers thereof, the weight of the flannel 115 120 125 130

thereby impedes the movement of ink through the portion of worsted which is compressed by the flannel. Consequently, transfer of ink from the flannel to the worsted occurs principally, if not entirely, at the extreme front edge of the flannel where the worsted is led therefrom. It will be appreciated that transfer of ink from the extreme edge of the flannel to the worsted cannot occur with such freedom as to supply the full feeding capacity of the worsted as readily as where the contacts throughout the worsted under the flannel is of such a nature that ink may flow freely to and in the worsted after once gaining access thereto. As a consequence, with the ordinary worsted used upon my device, there is a noticeable absence of stoppage of machine or faulty work because of failure of ink to flow, and also it is possible to operate the machines at higher speeds with good results.

The plates 15 and 16 are secured directly together, by a resilient connection at their rear parts, this connection consisting of screws 39 engaged in alined countersunk openings in each plate, and a spring 43 having pairs of opposed screws screwed into its ends, the spring having outturned ends engaged slidably in the sides of the openings through the plates as at 44 in Figures 13 and 14. The springs are moderately heavy so as to draw the plates together with a clamping action on the cams, whereby accidental movement of the cams is guarded against.

By the use of the soft rubber strip 33 between the clamping plates, when the pens are interposed between the rubber strip and one plate, and the plates operated to properly clamp the pens and the strip, the pen bases are embedded in the rubber which becomes fitted closely therewith, so that the space between the plates intermediately of the pen is snugly closed and access of ink thereto prevented. Also, a firm clamping of all pens is assured without requiring an extremely accurate planiform finish on the faces 18 or uniform thickness in the pen bases; or in case the plates should be slightly sprung by a lack of uniformity in positioning of the cams or machining of the bearing faces 28 engaged by the cams. Also, in cases where the pens are frequently used in certain positions and occasionally other pens are required to be introduced in other positions, wearing of the clamping faces engaging the pens or of the pen bases will not prevent them from being all securely and tightly clamped at all times. By the use of rubber, unequal thickness in the bases of the pens is also prevented from affecting the security with which the pens are held in the device.

It will be seen that the clamping plates are secured in pivoted relation easily by the

single hinge pin, which is adapted for easy removal to permit separation of the plates. Also, the only additional element required for operation of the plate is the cam shaft laid between the plates, rotation of which effects the clamping operation or release of pens as required.

I claim:

1. In a clamp of the character described, plates pivotally connected medially approximately along their longitudinal axes, said plates having jaw parts at one side of the pivot axis, and cams operative between the plates at the opposite side of the pivot axis from said jaw parts, means to operate the cams, and separate means to draw the plates together upon the cams.

2. As an improved article of manufacture in pen clamps, an elongated top clamping plate constructed for cooperative connection with a bottom member having a pen gripping inner face, and a top face extending into close proximity with said gripping face formed with a multiplicity of closely spaced grooves throughout its length, extending transversely of the plate from closely adjacent said gripping face.

3. A pen clamping plate for the uses indicated comprising a body of aluminum having a forward lower pen-gripping face, and a feed face extending upwardly from the gripping face and curved rearwardly, a multiplicity of grooves being formed in the feed face extending from closely adjacent the gripping face toward the rear and of a size to receive loosely a worsted or the like.

4. A pen clamp comprising opposed lower and upper plates having forward pen-gripping faces, the plates having ears projected therefrom in lapped relation and apertured in alignment, a hinge pin commonly engaged through the ears, a rock shaft having a plurality of cam elements thereon, one plate having notch bearings for the shaft, the other plate being recessed to receive the cams and having wiper faces opposed to engage the cams respectively, and means to rock the shaft and hold it in adjusted positions.

5. In a ruling device, a pen, a member thereover having a groove leading toward the pen, a loose fiber capillary ink feeding member laid in the groove and extended to the pen, and a fibrous body laid across the groove and in a relation to the member in the groove to feed ink thereto by capillary action, but not compacting the member in the groove.

6. In a clamp of the character described, plates pivotally connected medially approximately along their longitudinal axes, said plates having jaw parts at one side of the pivot axis, cams operative between the plates at the opposite side of the pivot axis from

the jaw parts, means to operate the cams and resilient means to draw the plates together upon the cams.

7. The structure of claim 1 in which the last named means comprises a close helical spring inserted through the two plates and screws snugly screwed into the respective

ends of the spring and having heads engaging the plates under contractile stress of the spring.

In testimony whereof I affix my signature.

JOHN KAEFER.
